US00D995104S

(12) United States Design Patent (10) Patent No.: US D995,104 S
Ren (45) Date of Patent: * Aug. 15, 2023

(54) BAG

(71) Applicant: SHENZHEN VAYI INDUSTRY CO., LTD., Shenzhen (CN)

(72) Inventor: Dehua Ren, Shenzhen (CN)

() Term: 15 Years

(21) Appl. No.: 29/892,731

(22) Filed: May 22, 2023

(51) LOC (14) Cl. 03-01

(52) U.S. Cl.

USPC D3/217

(58) Field of Classification Search

USPC D3/215-218, 225, 226, 231, 232,
